UNITED STATES PATENT OFFICE.

ERNST FREY, OF TROISDORF, NEAR COLOGNE, GERMANY, ASSIGNEE, BY DIRECT AND MESNE ASSIGNMENTS, OF ONE-FOURTH TO JOHAN NICOLAYSEN, ONE-FOURTH TO THOMAS B. DANCKWORTT, AND ONE-HALF TO FRANK H. OSGOOD, ALL OF SEATTLE, WASHINGTON.

METHOD FOR REGULATING THE FUEL SUPPLY WITH COMPRESSORLESS HIGH-PRESSURE CRUDE-OIL ENGINES.

Application filed January 4, 1923. Serial No. 610,656.

To all whom it may concern:

Be it known that I, ERNST FREY, a citizen of the German Republic, residing at Troisdorf, near Cologne, Germany, have invented certain new and useful Improvements in a Method for Regulating the Fuel Supply with Compressorless High-Pressure Crude-Oil Engines, of which the following is a specification.

10 This invention relates to an adjustable fuel pump for compressorless crude oil engines in which the efficiency and number of revolutions are influenced by altering the duration of injection.

15 The quantity of fuel supplied is adjusted to the actual charge of the engine in the improved pump in a similar manner as with pumps of known construction, by means of a pressure regulator, however, with the essential difference that a spring-controlled piston situated in the pressure pipe of the pump serves for positively controlling the pump and for consequently regulating the quantity supplied.

25 In order that the invention may be clearly understood, I shall proceed to describe the same with reference to the several forms of construction shown by way of example on the accompanying drawings, wherein:

30 Figure 1 shows in section a motor-cylinder with the improved device.

Figure 2 shows in section a modified construction of the piston which controls the pump.

35 Figure 3 shows in section a pump with variable piston stroke.

Figure 3^a is a section on line A—A of Figure 3.

40 Figure 3^b is the valve diagram.

Referring to Figure 1 of the drawings: *a* is the engine cylinder, *b* the body of the nozzle, *c* the spindle and *d* the cone of the fuel valve. The fuel valve *d*, under the pressure of spring *f*, shuts off the fuel passage *e* of the nozzle from communication with the combustion space, said passage *e* being exposed to the pressure of the fuel.

45 A roller *g* is arranged in a slit at the upper end of the valve spindle *c* and is designed to be raised by the oscillating lever *h* during the injection of the fuel, the oscillating lever *h* being actuated from the eccentric

k, as by means of the connecting rod *i*.

It is known that by means of the Lentz link motion adopted from steam engine 55 practice a variable duration of the opening period of the valve can be obtained with approximately uniform starting point of this period, for instance by means of a drum governor and double eccentric. Instead of 60 the Lentz link motion any other link motion for variable duration of the opening period could be used.

For any size of charge the fuel pressure must be approximately the same in the passage *e*, the value of this pressure (approximately 250 atms.) depending on the degree of the atomizing required. The atomizing proper takes place exclusively through the narrow boring *l* of the nozzle. 70

The fuel pressure is produced by the fuel pump *m* connected with the engine cylinder. This pump is suitably driven, as from cam *n* keyed upon the cam shaft and indicated in dash lines, said cam pressing downward 75 the pump piston *q* through a suitable connection, as the bellcrank lever *o* and the link *p*. At the suction stroke piston *q* is raised by means of spring *r*. For regulating the quantity of fuel to be supplied the 80 pump may be provided for instance with a back-flow suction valve *s* of known type which is controlled by the lever *t* and by one or several pressure valves *u*. The pressure pipe *v* connects the pressure space of 85 the pump with the fuel passage.

With the regulating lever *t* is connected, on the one hand the link *w* positively operated by the bell-crank lever *o*, and on the other hand the automatic pressure regulator *x—y—z* which serves for positively adjusting the control of the pump and consequently the quantity of fuel supplied. 90

If the pressure in the passage *e* becomes too great it is transmitted through the pressure pipe *v* to the space below the piston *x* which is thus raised against the compression of the spring *z* located in the guide *y*. The pivot of the regulating lever *t* mounted in the guide *y* is thus raised also and the 100 quantity of fuel supplied by the pump is reduced, inasmuch as the valve *s* is held open during a greater period of time.

By selection of the strength of spring *z*

the variations of the fuel pressure can be reduced to a minimum value.

In Figure 2 the piston x is shown as composed of several parts, for instance three parts. In this manner the manufacturing of the piston is facilitated and for the same total length a much better packing is insured without the danger of warping and jamming at fluctuations of temperatures.

- 10 The pressure pipe v for the fuel is connected with the regulator piston. The several piston elements e' , d' , f' are located in the guide bushings g' , h' , i' and have reduced or conical ends in order to prevent a jamming in the adjacent bushing when the piston is working. The guide bushings are pressed strongly against one another in a casing k' by means of a screw l' . The spring z which acts upon the subdivided piston, the guide y for the same, and the lever t acting upon the link motion of the pump, are the same as in Figure 1.

By means of such subdivided piston the leakage, even at pressures of 300 atms. and more, can be reduced to a minimum. Instead of the pump shown in Figure 1 with back-flow suction valve control, any other type of pump with variable delivery can be used, for instance a pump with variable piston stroke.

In Figures 3, 3^a, and 3^b a pump is shown the stroke of which is controlled positively from a spring-controlled piston situated in the pressure pipe. According to the valve diagram shown in Figure 3^b, the reciprocating driving rod l communicates an oscillating motion to the lever 3 fulcrumed at 2. The fulcrum 2, as shown, consists of a bolt pivotable in a straight guide 4 in which the lever 3 executes a short sliding movement when pivoting. From lever 3 the pump-stroke is transmitted to the pump piston 6 by means of the link rod 5.

The positions of the driving lever 3, which for the two dead point positions are shown in full lines, correspond to the largest pump stroke S_v which is effective at full load. In order to reduce the stroke of the pump the straight guide 4 and consequently the fulcrum 2 is shifted to the right, whereby lever 3 is made to slide in the pivot bolt 2. The extreme right hand position of fulcrum 2, which is designated by 2', corresponds to the smallest pump stroke. Lever 3 assumes in this position the two extreme positions indicated in dash lines. The pump stroke is of the smallest amount sL corresponding to "no load." The stroke can be reduced to zero with the aid of a convenient construction.

In Figures 3 and 3^a, 1 designates the driving rod, 2 the fulcrum of the oscillating lever, 3 the oscillating lever, 4 the straight guide designed to displace the fulcrum 2, and 5 the articulated rod for transmitting

the stroke upon the piston 6. In the pump casing 7 the straight guide 4 is adjustably mounted. The adjustment is effected by means of an adjusting lever 9 pivoted at 8. The spring 10 acts upon this adjusting lever 9 in the sense of increasing the stroke, while piston 11 acts upon the same in the sense of reducing the stroke.

The operation is as follows:—

The pump sucks the fuel in through the suction valve 12 and forces the same through the pressure valve 13 to the point where it is to be used. The position of the regulating lever shown corresponds to the largest delivery. As soon as the amount of charge to the motor decreases the pressure in the pressure pipe is increased.

The increased fuel pressure acts immediately upon the regulating piston 11, which in opposition to spring 10 adjusts a correspondingly smaller pump stroke by means of a lever 4, which shifts the pivot bolt 2. Inversely a movement of the several parts in opposite direction takes place under the pressure of spring 10 as soon as the amount of fuel supplied to the motor is increased, which would be accompanied by a reduction of pressure in the pressure pipe.

The piston 11, controlled by spring 10, therefore automatically regulates the pump stroke in such a manner that notwithstanding the varying load an approximately constant fuel pressure is obtained, or only quite small fluctuations of the fuel pressure occur, which can be regulated at will by corresponding selection of spring 10.

In Figure 3 a control of the suction valve 12 by means of link 14 and lever 15 is further indicated. This control is not adjusted during the service and is merely designed to insure that after the closing of the suction valve acting as back-flow valve, the pump is filled with fuel even at a high number of revolutions.

This mechanism serves therefore not for regulating the pump, but with the aid of the adjusting screw 16 of lever 15 the time of commencement of the pump stroke can be regulated. For the variation of the fuel pump stroke a large number of other well known stroke-adjusting devices are available. It is essential only that the adjusting of the stroke is effected positively by a spring-controlled piston situated in the pressure space or in the pressure pipe.

The improved pump presents special advantages for automobile engines. For varying the number of revolutions no adjusting of the pump by the driver is required. The driver has merely to adjust the duration of the open position of the fuel valve. At the stopping of the engine the injecting period of the fuel valve is merely reduced to zero while at the pump no adjustment takes place. The fuel pressure is maintained constant and

the delivery is correspondingly controlled automatically and positively.

In order to prevent a stronger drop of the fuel pressure during the injection of the fuel, and air chamber a' is arranged upon the nozzle body as shown in Figure 1, this air chamber communicating with the fuel passage and carrying a manometer b' for indicating the fuel pressure. The air chamber assists in the action of the control piston but it would not be necessary if the pressure pipe is comparatively flexible. Before the engine is started after a longer period of rest a sufficiently high injecting pressure has to be produced in the air chamber by pumping by hand or, with larger machines, even with the aid of auxiliary motors. With this object in view a square for a hand lever c' is arranged upon the angle lever o as shown in Figure 1.

I claim:—

1. In combination with a fuel pump for engines of the class described including a suction valve and a pump plunger, and having a pressure passage leading from said pump, means operatively connecting said plunger and suction valve to positively control closure of the latter in accordance with the piston stroke, and a spring-controlled piston in communication with said pressure passage operable to positively adjust the time of closing said suction valve in accordance with the pressure in said pressure passage, thereby to vary the delivery of the pump.

2. In combination with a fuel pump for engines of the class described including a pump plunger, and a suction valve, and having a pressure passage leading from said pump, a spring-controlled piston in communication with said pressure passage, a control lever operatively connecting said piston and said suction valve, to positively open the latter at each suction stroke of the plunger, and means for operating said lever and the pump plunger in unison.

3. In combination with a fuel pump for engines of the class described including a suction valve, and having a pressure passage leading from said pump, a spring-controlled piston in communication with said pressure passage operable to positively adjust said suction valve, thereby to vary the delivery

of the pump, said piston being composed of several elements, a bushing guiding said piston and likewise composed of several parts, and means for tightly packing the several parts of said guide bushing.

4. In combination with a fuel pump for engines of the class described including a suction valve, and having a pressure passage leading from said pump, a spring-controlled piston in communication with said pressure passage operable to positively adjust said suction valve, thereby to vary the delivery of the pump, said piston being composed of several elements, each having conical ends, a bushing guiding said piston and likewise composed of several adjoining parts, the ends of the piston elements being movable past the joints between the bushing parts, and means for tightly packing the several parts of said guide bushing.

5. In combination with a fuel pump for engines of the class described including a pump plunger and a suction valve, and having a pressure passage leading from said pump, said suction valve having an externally projecting stem, a spring-controlled piston having its axis parallel with and offset from said suction valve stem, and in communication with said pressure passage, a lever fulcrumed upon said piston and engageable between its ends with said suction valve stem, and means operatively connecting the outer end of said lever with the pump plunger, to positively control the time of closing said suction valve in accordance with the plunger stroke and the pressure in said pressure passage.

6. In combination with a fuel pump for engines of the class described including a constant-stroke pump plunger and a suction valve, and having a pressure passage leading from said pump, said suction valve having an externally projecting stem, a lever engageable with said stem to control the time of closure of said valve, a fulcrum member supporting one end of said lever and shiftable under the influence of pressure in said pressure passage, and means operatively connecting the opposite end of said lever with said pump plunger.

In testimony whereof I affix my signature.

ERNST FREY.
